ELECTRICAL RESISTOR AND METHOD OF
MAKING SAME

Melvin Arnold Thom, Rochester, N. Y.

Application March 27, 1951, Serial No. 217,785

14 Claims. (Cl. 201—67)

1

The present invention relates to wire-wound electrical resistors and to a process of manufacturing the same. This application is a continuation-in-part of my pending application Serial No. 55,193, filed October 18, 1948, now Patent No. 2,553,798, granted July 3, 1951.

It is always desirable to keep the weight of any part used in an airplane to a minimum. With the continuously greater and greater heights to which airplanes are required to fly both for commercial and martial purposes, and with the increasingly greater speed at which they fly, resistors of greater and greater capacity are continuously being required. Heretofore an increase in the capacity of a resistor has ordinarily only been attainable by an increase in size.

Compactness is also a feature desirable in parts employed in an airplane. If they project unnecessarily they get in the way and reduce the amount of available space. Heretofore resistors for use in airplanes have been encased in housings which have required mounting upon a side of the instrument board or chassis of the electrical equipment with which the resistors are to be used.

Resistors employed in naval vessels are always subjected to the corrosive action of salt water, but with the longer and longer tours of duty required in time of war, the problem of protecting the resistors used on a naval vessel against the action of the salt air and spray becomes more and more difficult.

One object of the present invention is to provide a wire-wound electrical resistor in which the windings are so well protected that it can be used successfully at high altitudes, as in airplanes, and that it will also be virtually impervious to the attack of sea water and salt air.

Another object of the invention is to provide a wire-wound resistor that, while small in size and compact, will be capable of withstanding large electrical loads and high temperatures without fracture or excessive heating.

A further object of the invention is to afford an efficient and durable resistor which is practical and economical to manufacture and that is especially adapted for electronic installations in airplanes and other applications where conservation of space is highly essential and where it is necessary for a resistor to have a high current-carrying capacity so as to conduct such currents as may be required without the parts becoming excessively heated or causing fracture, damage, disintegration, or lessening of the efficiency of the resistor.

Another object of the invention is to provide

2

a resistor mounted in a housing of metal or other heat conducting material in such a way as to be effectively insulated therefrom electrically but in such way also as to permit a large part of the heat generated by current passing through the resistance wire to be conducted away and dissipated so that the surfaces of the metal housing and the surface of the metal chassis adjacent to the housing cannot become excessively heated, and the resistor is protected from fracture or the damage that might otherwise result from electrical overload or excessively high temperatures.

A further object of the invention is to provide a resistor that may readily be mounted on or removed from a metal chassis.

Another object of the present invention is to provide an electrical resistor which can be threaded directly into a hole in the chassis of the electrical equipment on which it is being used. Thus, when the resistor is mounted on the chassis it will project a minimum distance therefrom.

Still another object of the invention is to provide a resistor with improved terminal portions.

Other objects of the invention will be apparent hereinafter from the specification and from the recital of the appended claims.

In the drawing:

Fig. 1 is a plan view with parts broken away to illustrate the structure of a resistor made according to one embodiment of the present invention and two successive steps in the manufacture of this resistor;

Fig. 2 is a plan view with parts broken away showing further steps in the manufacture of this resistor;

Fig. 3 is a sectional view, with parts broken away showing the method of assembling the resistor in its housing, and showing one form of housing constructed according to the present invention;

Fig. 4 is a plan view with parts broken away showing the resistor assembled in the housing and illustrating further steps in the manufacture of the resistor;

Fig. 5 is a fragmentary plan view, with parts broken away showing the final step in the manufacture of the resistor;

Fig. 6 is a sectional view on a reduced scale showing one way of mounting this resistor in a chassis; and

Fig. 7 is a corresponding view showing a modified form of mounting.

In the manufacture of a resistor according to the present invention a hollow ceramic cylindrical

core 10 is used, the ends of which are closed by metal conducting caps 11, only one of which is shown in Fig. 1. Each of these caps has a conducting wire 12 welded or otherwise secured centrally therein to project from its end; and the wires 12 project, therefore, from opposite ends of the resistor body. Each cap is also provided with a plurality of tabs or lugs 14. These tabs or lugs, as disclosed in my U. S. patent application Serial No. 31,236, filed June 5, 1948, now Patent No. 2,524,550, granted October 3, 1950, are equally spaced around each cap. The wire 15 of the resistor is secured at one end to a lug 14 of one cap 11, wound on a conventional winding machine around the ceramic body 10, and secured at its opposite end to a lug 14 of the other cap 11. As explained in my application above mentioned, the lugs permit of providing a winding of the desired resistance to a very close degree. With this construction of cap and the procedure described, it is possible to construct a wire wound resistor with no substantial variation from the required resistance. This makes it possible to utilize resistors made according to the invention in cases where a tolerance of even a fraction of a percent is all that is permissible.

After the wire 15 is fastened to the caps 11 as shown in Fig. 1, the attaching lugs 14 are bent over on the cylindrical portions of the caps. Then the entire unit is coated with any suitable insulating and sealing material, such as a silicone varnish or other plastic, so that the coating 17, only part of which is shown in Fig. 1, completely covers and seals the wire winding 15 and also the conducting caps 14 around the core 10, as shown at the left of Fig. 2, so that the porcelain core or body 10 and the interior of the resistor is effectively sealed against moisture. The wire wound resistor is then baked.

The resistor with its baked coating 17 is then placed in a woven sleeve 20 (Fig. 2) made of fiber glass or other suitable insulating material that fits snugly around the coated resistor. Then the sleeve-covered resistor is dipped in an electrically-insulating silicone varnish, shellac, plastic, resin, or other suitable material and baked. The sleeve 20 is preferably made at least as long as the resistor and is sufficiently porous to begin with so that the varnish, shellac, or other insulating material 21 permeates the sleeve and fills in to some extent the depression between the caps.

A resistor is limited in the load it will carry depending on its size, and in order to accommodate the maximum load required, it is necessary to employ ordinarily much larger resistors than desirable in order to prevent excessive heating, fracture, or other damage. It is essential and important to provide for greater heat dissipation than heretofore possible in order to make a resistor of small size carry maximum loads. To accomplish this, a resistor made according to the present invention is mounted within a rigid housing 25 (Fig. 4) of aluminum or other metal, or suitable heat conducting material, and this housing is constructed for attachment to a metal chassis or support which acts to dissipate readily and effectively the heat generated by any load to which the resistor may be subjected.

In order to insulate the resistor effectively and adequately from the surrounding metal housing and to insure fast and thorough heat dissipation, there is provided a body of electrically insulating material which entirely fills the space surrounding the resistor and between it and the metal housing, this insulating material being applied in such

a way as to avoid the possibility of any air pockets or voids remaining in the space surrounding the resistor and between the resistor and the housing.

After covering the resistor with sleeve 20, dipping the sleeve-covered resistor in an insulating material, and baking it, then, an elongated flexible sleeve 22 (Fig. 3) is fitted over the sleeve 20. This flexible sleeve 22 is also preferably made of woven fiber glass or other suitable electrically-insulating material and is made of a size to fit snugly around the sleeve 20 and over the ends of the resistor. It is also made long enough so that it can be used, as will be described below, as a means for pulling the resistor into its housing 25.

The resistor with the woven fiber glass sleeve 22 in position is then dipped or otherwise impregnated with a silicone or resin varnish, plastic, or other electrically-insulating material to saturate the fiber glass sleeve 22 thoroughly and form a slight coating thereon. Then the resistor is again baked.

It will be understood that the opening 26 in the housing is of a diameter to accommodate properly the resistor and surrounding insulating sleeves with the plastic material saturating the latter, so that when the resistor unit is inserted in the opening 26 within the metal housing 25 it fits tightly therein. The sleeves 20 and 22 are selected of a size so as to fit closely around the resistor and to fill the space between the cylindrical surface of the resistor and the surrounding surface of the metal housing.

The insulating material being in a plastic state fills in completely any space between the sleeve and the inside of the bore 26 of the housing, as denoted at 27 (Fig. 4), eliminating any possible air pockets or voids.

A filler 34 (Fig. 5) of silicone varnish or other insulating material is then placed over the ends of the housed and sleeve-covered resistor; and the resistor is then heated to say 125° C. to drive off the solvent. Then ceramic washers 39 are placed over the ends of the housing by threading the ends 32 of the sleeve 22 through central holes in the washers, as shown at the right in Fig. 4; and the washers are forced home, as shown at the left in Fig. 4. The washers cause the sleeve 22 to be tucked in around the ends of the resistor, squeezing the plastic filler 34 around the ends of sleeve and sealing the space between the bore of each washer and the sleeve and at the same time sealing the inside of the turned over portion 35 (Fig. 5) of the sleeve to the end of the resistor. The washers being of material thickness push the varnish up and around the sleeve 22 and complete the seal.

Then the whole unit is baked for say eight hours at say 150° C. and the temperature is then raised to say 250° C. and the bake continued for say one and a half hours. During this time, the plastic coating 20 of the resistor becomes sufficiently plastic to go into and seal any space between the sleeve and the resistor, as denoted at 36 in Fig. 5. Then the ends of the sleeve are cut off, as shown in Fig. 5. The conductor wires 12 are then flattened to form ears 40 and punched to form holes 41 (Figs. 6 and 7) to provide terminals.

The housing 25 is threaded along a portion of its periphery, as denoted at 29. This thread forms not only a means for securing the housing in a chassis, but also serves to dissipate heat.

Fig. 6 shows the completed resistor mounted in position in a chassis or board 45. It is passed

through a hole 46 in the chassis and is secured in position by nuts 47 which are threaded on threaded portion 29 of the housing from opposite ends thereof and which abut at opposite sides against the chassis.

The invention is not limited to a housing of the form described, but may be embodied in other forms of housings. For instance, the housing may have a smooth peripheral surface for a portion of its length, as denoted at 50 in Fig. 7 and may be turned down to a smaller diameter along the adjacent portion of its length and threaded, as denoted at 51. Such a housing can be fastened in a chassis 45 by passing the smaller diameter threaded portion 51 through the hole 46 in the housing to abut the shoulder 48 formed at the juncture of the larger and smaller diameter portions of the resistor against one side of the chassis and by threading a nut 47 on the threaded portion 51 of the resistor to abut this nut 47 against the opposite side of the chassis.

It is not possible with resistors as heretofore constructed to mount a resistor on a metal chassis in an electronic installation; the resistor must be suspended by brackets. With the present structure, however, the resistor can be mounted directly in the chassis. Moreover, with the construction described, a resistor having an actual length of approximately one inch and a maximum diameter of approximately five sixteenths of an inch will withstand electrical loads that otherwise would require a resistor of approximately five times that size. Actual tests have shown that in a resistor constructed according to the present invention and having a capacity of twenty-five watts, a current load of ten watts, for instance, produces a temperature at the outside of the unit of only 40°C., whereas a similar sized resistor of conventional construction and having no metal housing generates a temperature of 250°C. when carrying the same load. Other tests have shown that with the present structure, a current load of twenty watts produces a temperature in the housing of only 80°C., and a current load of thirty watts produces a temperature in the housing of only 119°C.

With resistors as heretofore constructed, a rated current load of thirty watts has required a resistor unit three inches long and five-eighths on an inch in diameter, whereas a resistor made according to the present structure occupying a space of approximately one-fourth that size can carry a current load of thirty watts and will generate a high temperature on the outside of the housing of only 119°C. as compared with the 250°C. temperature generated by the conventional thirty watt unit. The structure of the present invention therefore possesses superiority and practical advantages that have not been possible with any of the resistor constructions heretofore available.

Resistors may be constructed according to the present invention in different sizes for varying capacities. For a five watt rating, for instance, the opening 26 in the metal housing 25 has a diameter of eleven thirty-seconds of an inch, and the metal wall above the opening a thickness of .07 inch.

With a five watt unit such as described above, a current of 30.2 watts was required to raise the internal temperature of the resistor to 251°C. whereas the temperature of a conventional resistor of the same size rose to 250°C. with only five watts of current, and fifteen watts rendered the conventional resistor useless.

While the invention has been described in connection with different embodiments thereof, it will be understood that it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. The method of producing an electrical resistor which comprises placing a wire-wound body, that has conductors extending centrally outwardly from its ends, in a porous, flexible sleeve made of electrical-insulating material and which is longer than said body, impregnating said sleeve with an electrical-insulating material, heating the whole to make the second-named insulating material plastic, inserting the whole into a tightly-fitting bore in a metal housing by first inserting one end of said sleeve into said bore and then pulling on said one end of said sleeve to pull the whole into said bore, and then baking the assembly.
2. The method of producing an electrical resistor which comprises placing a wire-wound body, that has conductors extending centrally from its ends, in a porous, flexible sleeve made of electrical-insulating material which is longer than said body, impregnating said sleeve with a liquid electrical-insulating material, baking the whole, heating the whole to render the second-named insulating material plastic, inserting the whole, while the second-named insulating material is plastic, into a tightly-fitting bore in a metal housing, which is longer than said body, by first inserting one end of said sleeve into said bore and then pulling on said one end to pull the whole into said bore, then passing each conductor and the corresponding end of the sleeve through a central hole in a washer which is made of insulating material and whose central hole has a diameter much less than the diameter of said bore, forcing the two washers into opposite ends of the housing whereby to gather the ends of the sleeve over the ends of the body and about the conductors, and baking the assembly.
3. The method of producing an electrical resistor which comprises placing a wire-wound body, that has cylindrical conductor wires extending centrally from its ends, in a porous, flexible sleeve made of electrical-insulating material which is longer than said body, impregnating said sleeve with a liquid electrical-insulating material, baking the whole, heating the whole to make the second-named insulating material plastic, inserting the whole into a tightly-fitting bore in a metal housing, which is longer than said body, by first inserting one end of said sleeve into said bore and then pulling on said one end to pull the whole into said bore, then passing each conductor wire and the corresponding end of the sleeve through a central hole in a washer which is made of insulating material and whose central hole has a diameter much less than the diameter of said bore, forcing the two washers into opposite ends of the housing whereby to gather the ends of the sleeve over the ends of the body and about the conductor wires, cutting off the ends of the sleeve to allow

the conductor wires to project therebeyond, flattening the extremity of each conductor wire, and punching a hole therein.

4. The method of producing an electrical resistor which comprises coating a wire-wound body, that has conductors extending centrally outwardly from its ends, with an electrical-insulating coating, pulling said coated body endwise into the bore of a metal housing, which is open at both ends and whose length is at least as great as that of the coated body and whose bore will tightly fit the coated body, while the coating is plastic, allowing the conductors to project beyond the ends of the housing, and baking the assembly.

5. The method of producing an electrical resistor which comprises inserting a wire-wound body that has conductors extending centrally outwardly from its ends into a woven glass sleeve, impregnating the sleeve with an electrical-insulating varnish, and, while the varnish is plastic, inserting the whole endwise into the bore of a metal housing whose length is at least as great as that of said whole and whose bore will tightly fit said whole, and baking the assembly.

6. The method of producing an electrical resistor which comprises winding resistance wire on a core made of an electrical-insulating material and which has metallic caps at its opposite ends from which project outwardly extending conductors, securing opposite ends of the resistance wire to the caps, covering the caps and resistance wire with an electrical-insulating material, inserting the covered whole into a sleeve made of an electrical insulating material and which is longer than the capped core, impregnating this sleeve with a liquid electrical-insulating coating, baking the so-impregnated sleeve-covered whole, then heating the so-impregnated sleeve-covered whole to render the coating plastic, inserting it into the tightly-fitting bore of a metal housing which is long enough to enclose the capped core, sealing the ends of the sleeve over the ends of the caps and about the conductors, and baking the housed whole.

7. The method of producing an electrical resistor which comprises placing a wire-wound body, that has conductors extending centrally outwardly from its ends, in a porous flexible sleeve made of electrical-insulating material and which is longer than said body, impregnating said sleeve with a liquid electrical-insulating material, baking the whole, heating the whole to render the second-named insulating material plastic, inserting the whole, while the second-named insulating material is plastic, into the tightly-fitting bore of a metal housing which is longer than said body by first inserting one end of said sleeve into said bore and pulling on said one end of the sleeve to pull the whole into said bore, sealing the ends of the sleeve over the ends of said body and about the conductors, and baking the housed whole.

8. The method of producing an electrical resistor which comprises winding resistance wire on a core made of an electrical-insulating material and which has metallic caps at its opposite ends from which project conductors, securing opposite ends of the resistance wire to the caps, coating the wire, and caps with a liquid electrical-insulating material, then baking, then placing the baked whole in a sleeve which is made of an electrical-insulating material and which is approximately as long as the capped core, impreg-

nating the sleeve with a liquid electrical-insulating material and baking, placing the sleeve-covered whole into a second sleeve which is longer than the capped core, impregnating the

5 second sleeve with a liquid electrical-insulating material and baking, then heating the double-sleeve covered whole to render the last-named insulating material plastic, and, while said last-named insulating material is plastic, pulling the double-sleeve covered whole into the tightly-fitting bore of a metal housing which is longer than said capped core, putting a plastic electrical-insulating material into the ends of said housing, threading the conductors and the opposite ends of the second sleeve through two apertured electrical-insulating washers to seal the ends of the second sleeve over the caps, baking the so-sealed whole, cutting off the ends of the second sleeve which protrude beyond the ends of the housing, and forming terminal-attaching portions on the protruding ends of the conductors.

9. A resistor comprising a wire-wound insulated core having conductor wires extending centrally from opposite ends thereof which are electrically connected to the wire-winding of said core, said wire-wound core being covered with an electrical insulating material, a cylindrical metal housing having a bore extending therethrough in which said covered-wire-wound core is mounted with said conductor wires projecting beyond the ends of said housing, said housing being of greater length than said covered core and the bore of said housing being of a diameter to tightly fit said covered core and having its ends sealed to form an air-tight enclosure for said covered core, said housing being externally threaded to be threadably mounted in a support.

10. In combination, a rigid cylindrical metal housing having an axial bore therethrough, a high-voltage electrical resistor having conductor wires extending centrally from the ends thereof, said resistor being mounted within said bore with the conductor wires extending centrally beyond the ends of said housing, said bore being of a size to fit closely about said resistor and the wall of said housing surrounding said bore being of substantial thickness, said housing being externally threaded for mounting in a support, and a body of electrical-insulating material around said resistor and entirely filling the space between the resistor and the housing and covering the ends of the resistor and surrounding the conductor wires at the ends thereof adjacent to the resistor.

11. A resistor comprising a wire-wound insulated core having conductor wires extending centrally from opposite ends thereof which are electrically connected to the wire winding of said core, a metal housing having a bore extending therethrough in which said wire-wound core is mounted with the conductor wires projecting beyond the ends of the housing, the bore of said housing being of a diameter to fit tightly said wire-wound core, electrically-insulating washers which fit around said conductor wires and which close the ends of said housing, and electrical-insulating material around said wire-wound core and entirely filling the space between the resistor and housing and sealing the openings between said washers and the conductor wires.

12. A resistor comprising a wire-wound ceramic core having a metallic cap closing each of its ends, each of which has a conductor wire extending centrally outwardly therefrom, a sleeve made of insulating material covering said wire-

wound core and said caps and surrounding the conductor wires at the ends thereof which are attached to said caps, a metallic housing having a bore in which the sleeve-covered, capped, wire-wound core is mounted, ceramic washers threaded over the conducting wires and the ends of said sleeve and closing the ends of said housing, and an electrical-insulating material impregnating said sleeve and entirely filling the space between said sleeve and said housing and the spaces between the washers and said capped core.

13. A resistor comprising a wire-wound core made of an electrical insulating material having a metallic cap closing each of its ends, each of which has a conductor wire extending centrally outwardly therefrom, a sleeve made of an electrical-insulating material covering said wire-coated core and said caps and surrounding the conductor wires at the ends thereof which are attached to said caps, a cylindrical metallic housing having a bore extending therethrough in which said covered, capped, wire-wound core is mounted with the ends of the conductor wires extending beyond the ends of said housing, washers made of an electrical-insulating material threaded over the ends of said sleeve and said conductor wires and closing the ends of said housing, and an electrical insulating material impregnating said sleeve and entirely filling the space between said wire-wound core and the housing and between said washers and said caps, said housing being externally threaded for threading into a mounting.

14. A resistor comprising a wire-wound elec- 35

trically- insulated core having metallic caps at opposite ends which are electrically connected to the wire winding of said core and which have electrical conductors extending outwardly therefrom, said wire wound core being coated with a baked insulating varnish, a sleeve of electrical-insulating material, which is impregnated with an insulating varnish and baked, covering with said wire wound core, a second sleeve made of an electrical-insulating material covering the first sleeve and the ends of said core and surrounding the conductors at the ends thereof which are attached to said core, a metallic housing having a bore extending therethrough in which the sleeve-covered wire-wound core is mounted with the conductors projecting beyond the ends of the housing, washers made of an electrical-insulating material threaded over the conductors and the ends of said sleeve and closing the ends of said housing, and an electrical insulating material impregnating said second sleeve and entirely filling the space between said second sleeve and the housing and the spaces between the washers and the core.
